KNITTING MACHINE

Hellmuth Hoeppner, Einsiedel, near Chemnitz, Germany, assignor to Maschinenfabrik Einsiedel, Einsiedel, near Chemnitz, Germany, a corporation of Germany

Application May 4, 1937, Serial No. 140,683

16 Claims. (Cl. 66—82)

The present invention relates to an improved mechanism for disconnecting the yarn feeding assembly including yarn carriers and singer slur-cock cams of a flat knitting machine of the general type having spring beard needles movable as a unit with relation to a press edge and independently movable yarn measuring sinkers, and more particularly to a mechanism of this general description which is well adapted to press off fabric held on the needles.

In machines of this general description, the pressing off of the finished fabric is ordinarily accomplished by disconnecting the yarn frictions so that no yarn is fed to the needles, and then turning over the machine to cast off the loops held on the needles. This operation, which is performed manually, consumes a considerable amount of time, and requires the services of a skilled operator to avoid improper handling and consequent damage to the machine.

It is a principal object of the present invention to provide in a machine of the character described a simple and effective mechanism for disconnecting the yarn feeding assembly including the yarn carriers and singer slur-cock cams which may be utilized to render the yarn feeding assembly inoperative during continued operation of the machine, and may be readily re-connected without disturbing the setting of the several co-operating mechanisms, and more particularly the yarn carriers for subsequent operation in the machine.

It is more specifically an object of the invention to provide a mechanism of this general description which is well adapted for controlling the operation of the machine to press off fabric held on the needles, and thereby to effect a considerable saving in the time ordinarily consumed for this operation.

With these and other objects in view, as may hereinafter appear, one feature of the invention consists in the provision of means for disconnecting the yarn feeding assembly including the carriers and slur-cock cams from the draw arm, which is permitted to continue its reciprocating movement so that these parts may be subsequently re-connected without otherwise disturbing the setting or timing of the several co-operating mechanisms of the machine.

Another feature of the invention consists in the provision of a latch connection between the draw arm and the yarn feeding assembly, and mechanism cooperating therewith to disengage the latch at one end of its stroke.

Another feature of the invention consists in

the provision of mechanism controlled from the pattern chain of the machine which acts when rendered operative to disconnect the yard feeding assembly from the draw arm with the carriers at the limit of their travel in one direction, and thereafter to again operatively connect the yarn feeding assembly to the draw arm for the beginning of a new operation.

The several features of the invention consist also in the devices, combinations and arrangement of parts hereinafter described which, together with the advantages to be obtained thereby, will be readily understood by one skilled in the art from the following description taken in connection with the accompanying drawings, in which Fig. 1 is a somewhat fragmentary view in front elevation of a heeling machine embodying in a preferred form the several features of applicant's invention, only so much of the machine having been disclosed as is believed necessary to illustrate the connection of the present invention therewith; Fig. 2 is a plan view of substantially the parts shown in Fig. 1; Fig. 3 is a sectional end view looking from the right of the machine, as shown in Figs. 1 and 2; Fig. 4 is a fragmentary plan view showing the operation of the singer slur-cock cams to advance the sinkers cooperating with the two needle banks of the knitting section; and Fig. 5 is a detail plan view illustrating particularly the singer slur-cock cams, together with their supporting and driving mechanism.

The invention is herein disclosed in a preferred form as embodied in a heeling machine of the general type illustrated in the application of Lambach, Serial No. 104,244, which is specifically adapted for the knitting of the heel flaps into a combination foot and leg stocking blank. The machine has in general the construction and arrangement of a flat full-fashioned type machine having spring beard needles 10 movable as a unit with relation to a press edge 12, knockovers 14 and independently movable yarn measuring sinkers 16. Each knitting section of the machine comprises two separated banks of needles onto which are topped those portions of the last course of loops of leg fabric to which the heel flaps are to be knitted. The machine is provided with two separate singer slur-cock and yarn carrier assemblies cooperating with the needle banks and arranged to be driven simultaneously in opposite directions.

The general organization of the machine will be evident from the drawings, in which the usual supporting frames are indicated at 20 connected

by the usual lower front rail 22, rear rail 24, head rail 26 and the work table 28. The several cooperating mechanisms of the machine are driven in the usual manner from a main cam shaft which extends along the length of the machine and is generally indicated at 30 in Figs. 2 and 3. The two banks of needles 10 forming the one knitting section illustrated in the drawings, are carried on a single needle bar support 32 to which are imparted the usual vertical and forward and back movements of the needle motion. The yarn feeding assembly of the machine illustrated comprises specifically a yarn carrier 34, a sinker slur-cock cam 36 cooperating therewith to cause the sinkers to kink yarn about the shanks of the needles of the left-hand bank, a yarn carrier 38 and a sinker slur-cock cam 40 similarly arranged for advancing the sinkers associated with the needles of the right-hand bank. As best shown in Fig. 2, the yarn carrier 34 is supported on a carrier bar 42 which is connected to be driven from a friction rod 44 by means of a friction 46. The yarn carrier 38 is similarly supported on a carrier bar 48 connected to be driven from a friction rod 50 by means of a friction 52. The friction rods 44 and 50 are connected to be driven one from the other simultaneously in opposite directions by means of a pinion 54 which meshes with a rack 56 connected to the friction rod 44, and a rack 58 connected to the friction rod 50. As best shown in Figs. 1 and 5 of the drawings, the slur-cock cam 40 cooperating with the right-hand bank of needles, is supported on a slide bar 60 rigidly connected by means of a bracket 62 to move with the friction rod 50. The slur-cock cam 36 is similarly supported on a slide bar 64 rigidly connected to move with the friction rod 44 by means of a bracket 66 and a cross pin 68 which is secured to a sleeve member 70 slidably mounted on a supporting bar 72. The sleeve member 70 is connected to move with the friction rod 44 and forms an actuating connection through which the entire yarn feeding assembly is driven.

From the preceding description, it will be understood that in the type of machine herein referred to, the entire yarn feeding assembly consists of the carriers 34 and 38, the carrier bars 42 and 48, the frictions 46 and 52, the friction rods 44 and 50 with their interconnecting pinion 54 and racks 56 and 58, the slur cock cams 36 and 40, the slide bars 64 and 60, the brackets 66 and 62, the pin 68, and sleeve 70.

The yarn feeding assembly above described is driven from a Coulier motion which may be of ordinary description, and as best shown in Figs. 1 and 3 of the drawings, comprises a cross shaft 74 connected to be driven from the cam shaft 30, and having mounted thereon a Coulier cam 76. There is also provided a draw arm 78 which is pivotally supported at its lower end on a pivot 80, and is operatively connected to the Coulier cam 76 by means of two rollers 82 and 84 which are supported to engage opposite sides of the cam 76. The roller 82 is pivotally supported on the draw arm 78. The roller 84 is supported on the lower end of a lever arm 86 arranged to turn about a fixed pivot 88 located directly above the axis of the cross shaft 74, and is connected by a cross link 90 to move with the draw arm 78.

In accordance with a principal feature of the present invention, the connection from the draw arm 78 for driving the yarn feeding assembly, is constructed and arranged to be disconnected at one end of the draw arm stroke, so that the

slur-cock cams and more particularly the carriers associated therewith, may be easily and effectively thrown out of operation during rotation of the main cam shaft, and may be again reconnected to feed yarn without loss of time and without any necessity for interference with the setting or adjustment of the several cooperating mechanisms of the machine. As applied to the present machine, applicant's mechanism for disconnecting the yarn feeding assembly is utilized to press off the needles at the completion of a knitting operation, and thereby to cast off the completed fabric preparatory to the starting of a new heeling operation. Further in accordance with the present invention, applicant's mechanism for disconnecting the yarn feeding assembly is arranged to be actuated by pattern control devices which act automatically to disconnect the yarn feeding assembly during one reciprocation of the draw arm to cast off the finished fabric, and thereafter to re-connect the yarn feeding assembly for the beginning of the operation upon a new blank.

The connection from which the yarn feeding assembly is driven comprises specifically a latch 92 pivotally secured to the upper end of the draw arm 78 and having formed in the under side thereof a vertically extending slot or recess 94 which is arranged for locking engagement with the cross pin 68 secured to the sleeve driving member 70. There are also provided on the under side of the latch 92 to the right of the slot 94, as viewed in Fig. 1, two oppositely inclined cam surfaces 96 and 98, the surface 96 being provided for engagement with the pin 68 when disengaged from its slot 94, and the surface 98 being arranged to cooperate with a latch control element in the form of a shiftable roller 100 for disengaging the latch. A lug 102 formed on the under side of the latch 92 provides a downward extension of the left-hand wall of the slot 94 to insure the re-engagement of the pin 68 in the slot 94. With this construction and arrangement of the latch, it will readily be seen that when the roller 100 is located in the path of reciprocation of the latch 92, the movement of the draw arm 78 to the right will cause the roller 100 to strike the cam surface 98 to lift the latch out of engagement with the cross pin 68, as indicated by the dot-and-dash position of the latch 92 in Fig. 1. The continued engagement of the pin 68 with the left side of the slot causes the driving member 70 to be moved to its extreme position to the right. As the draw arm now begins its return movement to the left, the pin 68, disengaged from its slot 94, will ride against the cam surface 96, thus causing the sleeve driving member 70 to be disconnected from the draw arm at the right-hand limit of its stroke, as shown in Fig. 1. Prior to the next stroke of the draw arm 78 and latch 92 to the right, the roller 100 is moved out of alignment with the latch, so that the latch, upon reaching its limiting position to the right, can drop into locking engagement with the cross pin 68 to re-establish the connection between the draw arm 78 and the yarn feeding assembly of the machine. The roller 100, as best shown in Figs. 1 and 3 of the drawings, is slidably supported on a rearwardly extending pin 104 rigidly secured in a bracket 106 secured to the head rail 26, for movement transversely into or out of the path of reciprocation of the latch 92.

The position of the roller 100 to disconnect the latch 92 is controlled automatically from 75

the pattern chain 108 of the machine through connections which comprise a bell-crank shift lever 110 supported on a stationary pivot 112, and having formed on the upwardly extending 5 arm thereof the two arms 114 of a shifting fork. The bell-crank shift lever 110 is connected to a downwardly extending link 116 having formed therein a slot 118 to receive a pin 120 providing a yieldable connection with a lever arm 122 secured to a forwardly extending rock shaft 124. A tension spring 126 connected between the pin 120 and a pin 128 on the link 116 tends normally to maintain the link 116 in a fully depressed position with the pin 120 in engagement with the upper end of the slot 118. Secured to the forward end of the rock shaft 124 is a downwardly extending lever arm 130 which is connected by means of a rod 132 to a lever 134 pivoted at 136 on the machine frame, and arranged 15 to be actuated by engaging contact with a pattern lever 138. Inasmuch as the construction and arrangement of the pattern chain and levers actuated thereby are well-known in the art, only a fragmentary showing of the same has been 20 made in Figs. 1 and 2 of the drawings. The pattern lever 138 is supported on the usual pivot shaft 140, and is provided with a downwardly extending portion for engagement with a button designated at 142 located on the pattern chain 25 108. In accordance with the usual construction in machines of this type, the pattern chain is arranged to be racked in timed relation to the rotation of the main cam shaft 30 by means of a cam actuated lever 144 supported on a stationary pivot 146, and arranged to impart a reciprocal movement to the pawl lever 147 and pawl 148 cooperating with ratchet 150 secured to one end of the supporting drum 152 for the pattern chain 108. The timing of the racking 30 movements imparted to the pattern chain 108 is such as to cause the button 142 to engage with and actuate the pattern lever 138 and intervening connections to shift the roller 100 before the draw arm 18 and latch 92 have been moved 35 sufficiently far to the left to enable the roller to move beneath the latch. Under these conditions, the roller will strike against the side of the latch, causing the pin 120 to ride downwardly in the slot 118 against the tension of the spring 126, which will then operate as the latch 92 continues its movement to the left, to move the roller into the path of the cam surface 98. Upon the return stroke of the latch 92 to the 40 right, the cam surface 98 will ride upon the roller 100 which is now in the path of travel of the latch 92 and therefore the latch will be raised to disengage itself from the pin 68. Thus the driving connection between the draw arm 18 and the friction rod 44 is interrupted. Attention is called to the fact that the length of each 45 chain button 142 is sufficiently long enough to hold the spring 126 under tension, thereby holding the roller in active position until such time as the latch 92 has made its stroke to the left and has made its stroke to the right. During the continued operation of the machine, the bump 142 is moved from beneath the pattern lever 138 causing the pattern control connections above described to return to their normal 50 inoperative position under the influence of a compression spring 154 coiled about the connecting rod 132 between a collar 156 secured to the rod and a supporting bracket 158. The rearward movement of the roller 100 under the influence of the spring 154 operates to permit 55

the slot portion 94 of the latch to drop into locking engagement with the cross pin 68 as the draw arm 18 and latch 92 are returned to their extreme position to the right. In this position which is substantially that shown in Fig. 1, the machine is now stopped, the carriers 34 and 38 being located at the inner limits of their travel in position for the topping of a new stocking blank onto the needles. 6

While the present invention is particularly applicable to a heeling machine of the general type herein specifically disclosed, in which only one set of knitting carriers is employed, so that no necessity for shifting carriers can arise before the start of a new operation on the machine, it will be understood that the invention in its broader aspects is not limited to the specific machine disclosed, but is more generally applicable to flat knitting machines of the general type having spring beard needles movable as a unit 10 and independently movable sinker elements under any circumstances which may arise in which it is desirable to disconnect the yarn carrier assembly from continued operation with the machine. 15

The nature and objects of the invention having been indicated, and a machine embodying the several features of the invention having been described, what is claimed is:

1. In a flat knitting machine having spring beard needles movable as a unit with relation to a press edge, and independently movable yarn measuring sinkers, the combination of a yarn feeding assembly including a yarn carrier and a sinker slur-cock cam, a main cam shaft for the machine, a Coulier motion comprising a cam 30 driven from the cam shaft, a draw arm, a connection from the draw arm for actuating the yarn feeding assembly, and pattern controlled means for disconnecting said yarn feeding assembly from the draw arm at the limit of its stroke in one direction to prevent movement of said yarn feeding assembly while the draw arm proceeds to the limit of its stroke in the opposite direction. 35

2. In a flat knitting machine having spring beard needles movable as a unit with relation to a press edge, and independently movable yarn measuring sinkers, the combination of a yarn feeding assembly including a yarn carrier and a sinker slur-cock cam, a main cam shaft for the 50 machine, a Coulier motion comprising a cam driven from the cam shaft, a draw arm, a connection including a latch for actuating the yarn feeding assembly from the draw arm, and a control member acting when rendered operative to 55 disengage the latch for a position of the draw arm at the limit of its stroke in one direction and to hold the latch in disengaged position for preventing movement of the yarn feeding assembly while the draw arm proceeds to the limit of its stroke in the other direction. 60

3. In a flat knitting machine having spring beard needles movable as a unit with relation to a press edge, and independently movable yarn measuring sinkers, the combination of a yarn 65 feeding assembly including a yarn carrier and a sinker slur-cock cam, a main cam shaft for the machine, a Coulier motion comprising a cam driven from the cam shaft, a draw arm, a connection including a latch for actuating the yarn feeding assembly from the draw arm, and means acting on the latch when rendered operative for disconnecting said yarn feeding assembly from the draw arm upon reaching its limit of movement in one direction whereby the draw arm 70 75

- may move to its limit of movement in the other direction without actuation of the feeding assembly, and means for automatically re-establishing said connection upon the return stroke of the draw arm to its limit of movement in the first mentioned direction.
4. In a flat knitting machine having spring beard needles movable as a unit with relation to a press edge, and independently movable yarn measuring sinkers, the combination of a yarn feeding assembly including a yarn carrier and a sinker slur-cock cam, a main cam shaft for the machine, a Coulier motion comprising a cam driven from the cam shaft, a draw arm, a connection including a latch for driving the feeding assembly from the draw arm, a control element acting when rendered operative to disengage the latch from the draw arm upon reaching the end of its stroke in one direction for preventing movement of the yarn feeding assembly while the draw arm proceeds to the end of its stroke in the other direction, a pattern chain for the machine, and connections therefrom for actuating said control member.
25. 5. In a flat knitting machine having spring beard needles movable as a unit with relation to a press edge, and independently movable yarn measuring sinkers, the combination of a yarn feeding assembly including a yarn carrier and a sinker slur-cock cam, a main cam shaft for the machine, a Coulier motion comprising a cam driven from the cam shaft, a draw arm, a connection from the draw arm for actuating the yarn feeding assembly, said connection including a latch pivotally supported to move with the draw arm, and means for disconnecting the latch to arrest the movement of said assembly at one end of its stroke comprising a cam surface on said latch, a cam roll, and means for moving the roll into the path of movement of the cammed portion of the latch to disconnect said assembly from movement with the draw arm.
6. In a flat knitting machine having spring beard needles movable as a unit with relation to a press edge, and independently movable yarn measuring sinkers, the combination of a yarn feeding assembly including a yarn carrier and a sinker slur-cock cam, a main cam shaft for the machine, a Coulier motion comprising a cam driven from the cam shaft, a draw arm, a connection from the draw arm for actuating the yarn feeding assembly, said connection including a latch pivotally supported on the draw arm, means for disconnecting the latch to arrest the movement of said assembly at one end of its stroke comprising a cam surface on said latch, a cam roll, and means for moving the roll into the path of movement of said cammed portion of the latch to disconnect said assembly from movement with the draw arm, and means operative prior to the return stroke of the draw arm to withdraw the cam roll to permit the re-engagement of the latch.
7. A fabric press-off mechanism for a flat knitting machine having spring beard needles movable as a unit with relation to a press edge and independently movable yarn measuring sinkers, which comprises a yarn feeding assembly including a pair of yarn carriers adapted to be simultaneously reciprocated in opposite directions, a main cam shaft for the machine, connections from the cam shaft for reciprocating said assembly, means acting when rendered operative to disconnect said assembly from said cam shaft to press off the fabric held on the needles, and pattern control means therefor.
8. In a flat knitting machine having spring beard needles movable as a unit with relation to a press edge and independently movable yarn measuring sinkers, the combination of a yarn feeding assembly, including a pair of yarn carriers adapted to be simultaneously reciprocated in opposite directions, a main cam shaft, connections from the main cam shaft including a reciprocating latch for connecting the assembly to the main cam shaft for the driving of the assembly, and control means for actuating the latch to disengage the assembly from said connections.
9. A fabric press off mechanism for a flat knitting machine having spring beard needles movable as a unit with relation to a press edge and independently movable yarn measuring sinkers, which comprises a yarn feeding assembly including a pair of carriers operatively associated to move in opposite directions, a main cam shaft for driving said assembly, connections between the main cam shaft and said assembly for the operation thereof including a latch, a pattern mechanism, and a device controlled thereby for actuating the latch to disrupt the operation of said assembly by said connections when said spring beard needles have completed a full cycle of knitting operations.
10. In a full-fashioned knitting machine, the combination of a pair of yarn carriers, mechanism for driving said yarn carriers in opposite directions including a friction rod, a main cam shaft, power transmitting mechanism interposed between the main cam shaft and said friction rod for the driving thereof including a latch having a disengageable connection with the friction rod, and pattern control mechanism for disconnecting the latch from the friction rod when said carriers have completed their yarn laying activities, said pattern control mechanism including a slidably mounted roller adapted to have a cam action with said latch, and means for giving periodic sliding movements to said roller.
11. In a full-fashioned knitting machine, the combination of a pair of yarn carriers, mechanism for driving said yarn carriers in opposite directions including a friction rod, a main cam shaft, means interposed between the main cam shaft and said friction rod for the operating of said mechanism including a latch having a disengageable connection with the friction rod, and pattern control mechanism for disconnecting the latch from the friction rod when said carriers have completed their yarn laying activities, said pattern control mechanism including a movably mounted element adapted to have a cam action with said latch, link mechanism for giving periodic movements to said element, and an actuator having a yieldable connection with said link mechanism for the operation thereof.
12. In combination with the Coulier oscillating draw arm and reciprocable friction rod of a full-fashioned hosiery knitting machine, releasable means normally establishing connection between said draw arm and friction rod for the reciprocating movements of the latter through the oscillating movements of the former, and a mechanism periodically operable to release said means for preventing reciprocating movements of the friction rod during the oscillating movements of the draw arm.
13. In combination with the pattern chain, the Coulier oscillating draw arm and reciprocable friction rod of a full-fashioned hosiery knitting

- machine, releasable means normally establishing connection between said draw arm and friction rod for the reciprocating movements of the latter through the oscillating movements of the former, and a mechanism controlled by the pattern chain and periodically operated thereby to release said means for preventing reciprocating movements of the friction rod during the oscillating movements of the draw arm.
14. In a flat knitting machine, a Coulier oscillating draw arm, a reciprocable friction rod, a reciprocable slur cam bar, means interconnecting the friction rod and slur cam bar for simultaneous reciprocation, releasable means normally establishing connection between said draw arm and interconnected friction rod and slur cam bar for the reciprocating movements of said interconnected friction rod and slur cam bar through the oscillating movements of the draw arm, and a mechanism periodically operable to release said means for preventing reciprocating movements of the interconnected friction rod and slur cam bar during the oscillating movements of the draw arm.
15. In a flat knitting machine, a Coulier oscillating draw arm; a yarn feeding assembly comprising a pair of reciprocable friction rods; means between said friction rods for simultaneous reciprocation thereof in opposite directions; a pair of slur cam bars; means intercon-
- necting one slur cam bar to one friction rod for unison reciprocation therewith; and means interconnecting the other slur cam bar to the other friction rod for unison reciprocation therewith; releasable means normally establishing connection between said draw arm and yarn feeding assembly for reciprocating movements thereof through the oscillating movements of the draw arm; and a mechanism periodically operable to release said means for preventing reciprocating movements of the yarn feeding assembly during the oscillating movements of the draw arm.
16. In a flat knitting machine having spring beard needles movable as a unit with relation to a press edge and independently movable yarn measuring sinkers, the combination of a yarn feeding assembly including at least a pair of yarn carriers adapted for simultaneous reciprocation in opposite directions, a main cam shaft for the machine, driving connections operatively associated with said cam shaft including a reciprocating latch for connecting the yarn feeding assembly to said cam shaft, and control means for actuating the latch at one end of its travel to disconnect the yarn feeding assembly from the cam shaft, said control means having means for re-engaging the latch to drive the yarn feeding assembly upon the return movement of the latch.

HELLMUTH HOEPPNER.
